J. F. LINDBERG

CONDENSER

Filed July 5, 1922

UNITED STATES PATENT OFFICE.

JOHN F. LINDBERG, OF CHICAGO, ILLINOIS.

CONDENSER.

Application filed July 5, 1922. Serial No. 572,873.

To all whom it may concern:

Be it known that I, JOHN F. LINDBERG, citizen of the United States, residing at Chicago, in the county of Cook and State 5 of Illinois, have invented a certain new and useful Improvement in Condensers, of which the following is a full, clear, concise, and exact description.

My invention relates to those condensers 10 whose sides are formed of substantially parallel leaves and resides in so mounting both condenser sides that each may be turned or otherwise adjusted with respect to the other to regulate the capacity of the 15 condenser. There is desirably an adjusting device individual to each condenser side for turning or otherwise adjusting it with respect to the other condenser side.

A condenser constructed in accordance 20 with the preferred embodiment of the invention includes a hollow shaft mounted to turn and carrying one of the condenser sides, sleeves upon which the other condenser side may turn, a shaft within the 25 bore of the hollow shaft, and speed reducing motion transmitting lever mechanism connected with the second shaft and in gear connection with one of the sleeves which is also in gear connection with the condenser 30 side supported thereby.

I will explain my invention more fully by reference to the accompanying drawing in which Fig. 1 is a side elevation, partially in section, of a condenser constructed in 35 accordance with the preferred embodiment of the invention; Fig. 2 is a sectional view on line 2—2 of Fig. 1; Fig. 3 is a view on a larger scale of a part of the structure as it is illustrated in Fig 2; Fig. 4 illustrates the lever mechanism, a plate of 40 one of the condenser sides adjustable thereby and a mounting for the plates of this condenser side, these elements being illustrated in separated relation; and Fig. 5 is 45 a view in perspective of one of the supporting sleeves.

Like parts are indicated by similar characters of reference throughout the different figures.

50 The condenser illustrated includes two mounting plates 1 and 2 of insulating material which are assembled upon threaded metallic rods 3 by means of nuts 4, 5, 6 and 7. These rods are assembled with the 55 mounting board 8. Sleeves 9 are mounted

to turn upon the rods 3 between the nuts 5 and 6. These sleeves are formed with ribs 10 that constitute elongated gear teeth, these ribs marginaling slots in the sleeves. The sleeves are also formed with ears 11 60 which embrace the ribs 10, the leaves 12 of one condenser side being carried by the sleeves 9 in the spaces between the ears 11 thereof. The sleeves and the parts thereon, being metallic, serve to electrically connect 65 the plates of the condenser side employing the plates 12. Mechanism hereinafter to be specified is employed for turning the sleeves 9 in unison whereby the leaves 12 may be turned upon a common axis when 70 the condenser side employing these leaves is to be adjusted to regulate the condenser capacity. The other condenser side is composed of a group of metallic leaves 13, these leaves being alternated with the leaves of 75 the first group, as illustrated.

The support for the group of leaves 13 which is rotatively mounted in the plates 1 and 2 is inclusive of a rotatable sleeve or hollow shaft that is composed of a metallic section 14 having an enlargement 15 journaled in the plate 2 and a contiguous section 16 of non-conducting material that is rotatively supported in the plate 17 through which the shaft section 16 projects. There is a knob 18 upon the outer end of the shaft section 16, this knob being provided with scale marks upon its periphery, this knob being rotatable in front of a suitably marked plate 19, whereby the 80 extent of rotative movement of the shaft 14, 16 and of the condenser side carried thereby may readily be determined. The metallic shaft section 14 is also journaled upon the plate 1 through the intermedia- 85 tion of a second shaft 20 journaled within the first shaft and having its projecting end 21 directly journaled in the plate 1. The portion of this shaft that is within the metallic section 14 is itself metallic. The 90 inner shaft has a section 22 of insulating material that is in threaded connection with the metallic portion of this shaft and which continues through the bore of the hollow shaft or sleeve sufficiently to project beyond the front of the knob 18, this projecting end of the inner shaft being equipped with a knob 23 that bears suitable scale marks upon its periphery to cooperate with suitable marking upon the knob 18 in defining 100 105 110

the extent of the adjustment of the inner shaft with respect to the hollow shaft.

The leaves 13 are spaced apart by metallic washers 24 and there is a nut 25 screwed upon the inner end of the hollow shaft 14 for clamping the leaves and washers and the shaft enlargement 15 together.

The coarse or approximate adjustment of the capacity of the condenser is effected by turning the knob 18 to cause the turning movement of the condenser side 13 at the speed of rotation of the knob. The finer or finishing adjustment of the condenser capacity is effected by turning the other condenser side 12 to which end the speed reducing motion transmitting mechanism is interposed between the inner shaft 22 and the sleeves 9. This speed reducing motion transmitting mechanism is preferably inclusive of a collar 26 of insulating material that is fixed upon the inner shaft 20 to turn therewith. This collar carries pins 27 that move within the slots 28 formed in the levers 29 longitudinally thereof. These levers are formed with openings 30 through which the rods 3 freely pass. These openings are formed with enlargements 31 that receive the ribs or elongated teeth 10 upon the sleeves 9. Whenever the knob 23 is turned the shaft 20 is turned to cause movement of the levers 29 and swinging movements of the sleeves 9 of reduced turning movement with respect to the movement of the knob 23. The sleeves 9 being in gear connection with the condenser leaves 12 through the intermediation of the elongated teeth 10, such condenser leaves are caused to turn as a consequence of the operation of the levers 29. In adjusting the condenser capacity the initial or approximate adjustment is effected by turning the knob 18 and the close or finishing adjustment is effected by turning the knob 23.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A condenser including two condenser sides formed of substantially parallel leaves and both mounted to turn; and an adjusting device individual to each condenser side for turning it with respect to the other condenser side, said adjusting devices being constructed to adjust the condenser sides pertaining thereto at different rates.

2. A condenser including two condenser

sides formed of substantially parallel leaves; a hollow shaft mounted to turn and carrying one of the condenser sides; a mounting upon which the other condenser side may turn; a shaft within the bore of the hollow shaft; and motion transmitting mechanism between this second shaft and the latter condenser side whereby rotation of the second shaft will cause this condenser side to turn. 70

3. A condenser including two condenser sides formed of substantially parallel leaves; a hollow shaft mounted to turn and carrying one of the condenser sides; a mounting upon which the other condenser side may turn; a shaft within the bore of the hollow shaft and speed reducing motion transmitting mechanism between this second shaft and the latter condenser side whereby rotation of the second shaft will cause this condenser side to turn. 80

4. A condenser including two condenser sides formed of substantially parallel leaves; a hollow shaft mounted to turn and carrying one of the condenser sides; sleeves upon which the other condenser side may turn; a shaft within the bore of the hollow shaft; and motion transmitting lever mechanism connected with the second shaft and in gear connection with one of said sleeves which is 90 also in gear connection with the condenser side supported thereby.

5. A condenser including two condenser sides formed of substantially parallel leaves; a hollow shaft mounted to turn and carrying one of the condenser sides; sleeves upon which the other condenser side may turn; a shaft within the bore of the hollow shaft; and speed reducing motion transmitting lever mechanism connected with the second shaft and in gear connection with one of the sleeves which is also in gear connection with the condenser side supported thereby. 95

6. A condenser including two condenser sides formed of substantially parallel leaves and both mounted to move; and an adjusting device individual to each condenser side for moving it with respect to the other condenser side, said adjusting devices being constructed to adjust the condenser sides 105 pertaining thereto at different rates. 110

7. A condenser including two condenser sides, both mounted to move; and an adjusting device individual to each condenser side for moving it with respect to the other condenser side, said adjusting devices being constructed to adjust the condenser sides pertaining thereto at different rates. 115

In witness whereof, I hereunto subscribe my name this 21st day of June, A. D., 1922. 120

JOHN F. LINDBERG.
